UNITED STATES PATENT OFFICE.

ADELMER M. BATES, OF CLEVELAND, OHIO, ASSIGNOR TO BATES VALVE BAG COMPANY, OF CLEVELAND, OHIO, A CORPORATION OF WEST VIRGINIA.

VALVE-BAG.

No. 907,558.

Specification of Letters Patent.

Patented Dec. 22, 1908.

Application filed January 6, 1906. Serial No. 294,843.

To all whom it may concern:

Be it known that I, ADELMER M. BATES, a citizen of the United States, residing at Cleveland, in the county of Cuyahoga and State of Ohio, have invented a certain new and useful Improvement in Valve-Bags, of which the following is a specification.

My invention relates to valve bags and has for its object to provide a bag which is temporarily closed at one end and provided with a valve at or near the other.

My invention is illustrated in the accompanying drawings wherein

Figure 1 is a side view of a valve bag with parts broken away, Fig. 2 is a view of the same with the open end tied.

Like parts are indicated by the same letter in all the figures.

A is the material and AA are the sides of the bag, B the valve made in any desired manner and of any desired material.

C is the lower finished edge of the open end of the bag. D is the string by which this lower end is temporarily closed when the bag is completed.

In some cases it is desirable to have a valve bag which is capable of use either as a valve bag or as the usual open mouth bag. At the same time it is desirable to have valve bags which are capable of being opened without injury to the bag for the purpose of emptying the contents. Many valve bags, such as the little cheap bags which are used for salt and other materials, are destroyed by the consumer of the material within the bag. In the case of larger and more valuable bags and where the material is valuable, it is not uncommon for the consumer to open the valve bag with such care that it is uninjured and can be again sewed up and can be used as a valve bag. It often happens, however, as for example in the case of cement bags, that

the bag is large and relatively valuable while the consumer is a disinterested workman. If he has any difficulty in opening the bag he is likely to tear it open or cut it open so as to make it valueless, whereas the practice is to return such bags for refilling. I meet these requirements by constructing the bag, which is in its completed form, as an inwardly opening valve at one end and is temporarily secured at the other. Such a bag can be filled through a valve in the usual manner with valve bags, and when the workman receives it he can open it in the most easy and convenient manner by jerking the string loose or cutting it. The contents then fall out at such opened end and the bag is uninjured. It is returned to the filling factory where the end is tied up to make a complete bag and it is then filled through the valve. In this manner the danger of having the bags destroyed is obviated no matter how careless, indifferent or reckless the workman using the bags may be.

I claim:

1. A bag having a filling opening with an inwardly opening valve to close the same and a temporarily secured discharge opening.
2. A valve bag tied at one end and having a filling opening at the other end with an inwardly opening valve to close the same at the other end.
3. A bag having a filling opening at one end with a valvular filling tube extending inwardly from said opening so that the filling opening is closed by the material in the bag when filled, said bag having an open mouth at the other end with means for temporarily closing said open mouth.

ADELMER M. BATES.
